UNITED STATES PATENT OFFICE.

JOHN A. BRILL, OF PHILADELPHIA, PENNSYLVANIA.

CAR-TRUCK.

SPECIFICATION forming part of Letters Patent No. 554,283, dated February 11, 1896.

Application filed July 5, 1894. Serial No. 516,553. (No model.)

To all whom it may concern:

Be it known that I, JOHN A. BRILL, a citizen of the United States, residing at Philadelphia, in the county of Philadelphia and State of Pennsylvania, have invented certain new and useful Improvements in Car-Trucks, of which the following is a specification.

My invention has relation to running-gear for street-railway or other cars whereon the axle-box pedestals are rigidly secured to the longitudinal sill-pieces of the car-body.

The main advantage derived from securing the pedestals to the car-body sill-pieces is one of economy in construction, as but two pairs of wheels need be used for the car. It has, however, long been recognized by those engaged in the art to which my invention pertains that such described connection of the pedestals to the car-body has its disadvantages in that the two pairs of wheels must be so located relatively to one another and to the transverse center line of the car-body, proportionately to the gage of the trucks, as to admit of the wheels turning or traveling on the short curves incident to street-railways. This central location of the two pairs of wheels necessarily restricts or limits the length of the car-body, and even with the length of the car-body used causes their ends to overhang to an undue extent, resulting in undue vertical vibration of the same and tendency to raise the forward wheels from the tracks, which imposes additional work on the motive power and increases the liability of the car jumping or running off the track-rails; further, as the axle-box pedestals are rigidly affixed to the car-body the movement of the wheels and axles in turning a curve produces undue friction and grinding of the axle journal-boxes in their bearings and also of the wheels on the rails, resulting in undue wear of said parts and additional work for the motive power. It has, further, long been recognized by those skilled in the art to which my invention relates that the above-described disadvantages might be overcome or avoided by providing truck-frames for the single pairs of wheels and pivoting or connecting the truck-frames near the ends of the car-body, as is done for the four or more wheel trucks for steam - railway cars; but as the truck-frames for the single pairs of wheels have

only one line of wheel-support upon the tracks it is essential that said frames be so constructed or pivoted to the car-body as to be unconnected or independent of each other, in order that the single pair of wheels for each truck-frame may separately move or conform to the curved portions of the track when traveling on the same, to avoid the friction and grinding of the wheels on the rails, and yet be incapable of such movement when traveling on the straight portions of the trackway to avoid jumping or running of the wheels off the rails. It is also essential that the truck-frames be prevented from vertically rocking on the axle-journals to avoid raising the wheels from the track-rails and liability of the car jumping the track when traveling upon either the curves or straight parts of the roadway. The accomplishment of these described functions or results is the object of my invention, and to this end I mount each single pair of wheels upon a truck-frame and connect the latter to the car-body by rub and pivot plates so constructed and arranged that the truck-frames are independent of each other or are unconnected, are incapable of rocking vertically upon the axle-journals and of swinging or moving laterally when traveling upon the straight portions of the track, but are capable of making such lateral swinging movement on curves to admit of the wheels conforming thereto, such movement being controlled by the car-body.

My invention accordingly is embodied in a truck-frame for a single pair of wheels having the axle journal-boxes mounted thereon and rub-plates between the truck-frames and car-body, which rub-plates are located in different transverse lines and, if desired, so configured that when the truck-frames move or swing laterally the car-body is by such movement raised or lowered to admit of the swinging movement of the truck-frames and also of the gravity or load of the car-body controlling or limiting the extent of the lateral swinging movement of the truck-frames, the latter having or not having, as desired, a central king-bolt connection with the car-body, which king-bolt when used is provided with a downwardly - acting spring - pressure to maintain such connection and admit of the vertical movement of the car-body as it turns

a curve or correspondingly moves under the influence of the lateral swinging movement of the truck-frames, all as hereinafter pointed out in the specification and set forth in the 5 claims.

- Reference being had to the accompanying drawings, Figure 1 is a side elevation, representing a street-railway car and truck-frames for single pairs of wheels, showing a form of 10 rub-plates between the car-body and truck-frames for raising and lowering the car-body vertically as the truck-frames swing laterally on curves or other parts of the track, the 15 brake-shoe and actuating mechanism therefor not being shown; Fig. 2, an elevation of one of said truck-frames and part of the sill-piece of the car-body drawn to an enlarged scale, showing brake-shoes and actuating mechanism therefor secured to said frame 20 and central king-bolt connection between the car-body and truck-frame; Fig. 3, a plan of a truck-frame removed from the car-body; Fig. 4, a longitudinal section through the center of a truck-frame, drawn to an enlarged 25 scale, showing more plainly the king-bolt connection between the car-body and truck-frame; Fig. 5, a transverse section, partly in elevation, of part of the car-body and truck-frame; Fig. 6, a view similar to Fig. 1, showing modified forms of the truck-frame and combined pivot and rub plates for connecting the car-body to the truck-frames; Fig. 7, a plan of the truck-frame shown in Fig. 6; Fig. 8, a sectional view, drawn to an 30 enlarged scale, of the combined rub and pivot plate shown in Fig. 6; and Figs. 9 and 10, plans showing different styles of truck-frames and different modes of locating thereon the rub-plates or combined rub and pivot plates. 35
- 40 A represents the car-body of the usual or any suitable style or form, B B the single pairs of wheel, and C C the truck-frames therefor, located adjacent to the ends of the car-body as shown or as desired.
- 45 The truck-frames consist preferably of the upper and lower arch-bars c c', respectively connected by end cross-bars c²c², of channel-iron, preferably as shown, and central pillars or columns c³c³ for the axle-boxes c⁴c⁴, 50 which may be of the form shown in Fig. 1, wherein the boxes have on each side spring-seats c⁵ with openings through which the columns c³c³ pass and between which and the upper arch-bar, c, and surrounding said columns are springs c⁶, or said boxes may be of 55 the form shown in Fig. 6, wherein the columns c³ form guides for the boxes c⁴ and the springs c⁶ are located between the top of the axle-boxes and the upper arch-bar, c.
- 60 At the four corners of the truck-frames, when made of rectangular or oblong form, as shown in Fig. 3, are represented rub-plates c⁸, which contact or engage with other rub-plates c³, secured to the bottom of the car-body. 65 The disposition or location of these rub-plates is such that they are not all in line with the transverse center of the truck-frame,

and support the car-body at four different points at each end of the same, and they prevent the truck-frames from vertically swinging or rocking upon the axle-journals. The contact-surfaces of the rub-plates c⁷c⁸ may be of any suitable configuration. In Figs. 1 to 5, inclusive, I have shown them having the oppositely-inclined surfaces c⁹c⁹ with intervening flat or horizontal surfaces c¹⁰, which fit one another and keep the truck-frames in alignment with the car-body and avoid any needless lateral swinging of the truck-frames when traveling upon the straight portions of the trackway, but which permit of such movement, duly controlled by the gravity of the car-body, when entering upon, traveling over, and passing away from the curves of the trackway. Thus when the wheels or 80 axles laterally move to the right or left to conform to the curves of the trackway the truck-frames correspondingly move, and in doing so one or the other of the inclined surfaces c⁹c⁹ of the rub-plates c⁷ on the truck-frames 85 slide or move upon the corresponding inclines of the rub-plates c⁸, secured to the car-body, to first vertically and successively elevate the ends of the same and then admit of said ends correspondingly descending or returning to 90 their normal position. This vertical movement of the car-body admits of the lateral swinging movement of the truck-frames, wheels, and axles on the curves, and the extent of said swinging movement of the wheels 95 and frame is limited or controlled by the load or gravity of the car to prevent the wheels jumping or running off the track-rails at the curves.

Any suitable lubricating devices may be 105 used for the rub-plates or they may be manually oiled from time to time, as required.

Instead of arranging the truck-frames and the rub-plates c⁷c⁸ as shown in Fig. 3 and as above described, the angles or corners of the 110 frames may be located at the transverse and longitudinal center lines of the same and the rub-plates correspondingly located, as shown in Fig. 9, in which case a pair of rub-plates is located over or above the axle-journals 115 and the remaining rub-plates occupy a position coinciding with the longitudinal center of the car-body, or all the rub-plates may be collected together in the form of an integral or other suitably-constructed annular ring located between the wheels concentric to the center of the truck-frame, as indicated in Fig. 10.

If desired, the inclined surfaces of the rub-plates may be dispensed with, as shown in 125 Figs. 6, 7, and 8, in which case they have tongue-and-groove contact-surfaces for admitting of the load or gravity of the car controlling or limiting the lateral swinging movement of the truck-frames.

The latter are pivoted or connected to the car-body in any suitable or desired manner, the pivotal connection in a measure depending upon the relative formation, construction,

and arrangement of the rub-plates. Thus for the form of rub-plates shown in Figs. 6, 7, and 8 said connections consist of bent plates or brackets *d* preferably secured to the car-body 5 and arranged to have their lower free ends enter the outside grooves *d'* in each of the lower or truck-frame rub-plates, *c'*, to provide a number of combined rub and pivot plate connections between the car-body and truck-frames, or said brackets *d* and grooves *d'* may be dispensed with and a central king-bolt used, as indicated by dotted lines *G*, Fig. 7. When the rub-plates are not tongued and grooved or are constructed as shown in Figs. 15 1 to 5, inclusive, the central-king-bolt connection *G* is preferably used, in which case the truck-frames may be provided with any suitable form of bolster or bolster-framing *F* for the king-bolt *G*. The truck-bolster bars 20 *F*, I prefer to make of channel or other suitable material grooved on its under side and with the channel or groove turned down, the ends *f* thereof being preferably filled up with blocks *f'*, as desired, for suitable end bearings and for bolt connection (not shown) with the cross-bars *c*². At right angles to the truck-frame bolsters *F* are car-body bolsters *a*, through which pass the king-bolts *G*, and between bolsters *a* and *F* are washers or other 30 rub-plates *a'*.

When the rub-plates having inclined contact-surfaces *c*³ *c*⁴ are used, the king-bolts *G* between the underside of bolsters *F* and plates *g*, suitably secured to the lower end of said 35 bolts preferably, are provided with spiral or other springs *g'*, which exert a downward pressure in addition to the load or gravity of the car-body and also serve to maintain the pivotal connection between the truck-frames 40 and body as the latter makes its vertical movement for admitting of and controlling the lateral swinging or rocking movement of the truck-frames when said inclined-contact-surface rub-plates are used.

45 The employment of the grooved or channel-iron bolster *F*, as described, affords ample space between the axle and the channeled part of the bolster *F* for a suitable length of spring *g'*, as well shown in Fig. 4.

50 The single pairs of wheels are provided with suitable brake-shoes and actuating mechanism therefor mounted upon the truck-frames, which actuating mechanism is connected or is in gear with any suitable hand or other operating lever on the car-body.

55 In Fig. 2 I have shown a preferable form of brake mechanism, wherein *h* *h* are the brake-shoes, located one on each side of the wheel and connected by beams *h'* hinged or linked; as shown at *h*², to brackets or hangers *h*³ secured to the truck-frame cross-bars *c*².

To one of the brake-beams is pivoted a lever *h*⁴, the lower or one end of which has a link connection *h*⁵ with the other brake-beam 65 of the truck-frame, so that a single movement of the lever *h*⁴ in one direction applies both

brake-shoes and its reverse movement releases the same.

From the foregoing it will be noted that the truck-frames for the single pairs of wheels 70 support the brake-shoes and actuating mechanism therefor; that the truck-frames cannot rock vertically upon the axle-journals, and that their lateral swinging movement is limited and controlled by the load or gravity of 75 the car-body.

I do not confine myself to the details of construction shown, as it is obvious that they may be varied without departing from the spirit of my invention, parts of which can be 80 employed on four-wheeled pivoted trucks.

What I claim is—

1. A car-body, and a truck pivoted thereto having a single pair of wheels and an axle 85 therefor, combined with truck-bearings on the truck-frame, the bearings having aligned and oppositely and upwardly inclined contact surfaces merging one into the other, car rub-plates having similarly-disposed but downwardly-inclined surfaces superposed on the 90 bearings and secured to the car-body, and a spring coacting with said rub-plates and bearings, and adapted to be compressed thereby when the car-body is moved out of line with the truck, substantially as described. 95

2. The combination with a car-body, of a truck-frame pivoted thereto and having a single pair of wheels and an axle, a part of the truck-frame at the corners extending transversely of the truck and part at an angle to the axle, truck-bearings located at said corners, said bearings having aligned and oppositely and upwardly inclined contact-surfaces merging one into the other, and superposed car rub-plates having similarly-disposed but 100 downwardly-inclined surfaces, and a spring coacting with said pivot and adapted to be compressed by the bearings and rub-plates 105 when the car-body is moved out of line with the truck, substantially as described. 110

3. The combination, with a car-body, and a truck pivoted thereto over its axle, of a bearing for the car-body having a reversely-inclined contact-surface, a coacting truck-bearing, and a spring coacting with said truck-bearing adapted to be compressed by the reversely-inclined surface of the body-bearing when the car-body is moved out of line with the truck, substantially as described. 115

4. The combination, with a car-body and truck-frame, of circular-arc and compound reverse-incline rub-plates and bearings upon the truck-frame and car-body, one of which is grooved to receive a tongue on the other to prevent lateral displacement, and one of which is also grooved to receive a circular-arc guide moving with the other to prevent vertical displacement, substantially as described. 125

5. The combination, with a car-body and truck-frame, of a circular-arc and compound reverse-incline rub-plates, car rub-plates and truck-bearings tongued and grooved to pre- 130

vent lateral displacement, said car rub-plates and truck-bearings being also provided, one with an exterior circular - arc horizontal groove, and the other with a corresponding rib in said groove to prevent vertical displacement, substantially as described.

6. The combination, with a car-body and a truck-frame, of rub-plates, bearings for the car-body upon the truck-frame having inclined contact-surfaces adapted to raise the car-body when diverted at an angle to the line of the truck-frame, and a spring bearing against the truck-frame and car-body and tending to restore the car-body to its normal position by being compressed when the car-body is raised, substantially as described.

7. A separate truck-frame and a car pivoted thereto and supported thereon over the axle of the truck, said truck-frame having a portion extending longitudinally beyond the axle, combined with a spring-supported truck-bearing and a rub-plate having aligned and oppositely-inclined surfaces secured to the car and to the truck-frame on said extended portion of the truck, and located in the longitudinal center of the truck-frame, substantially as described.

8. The combination with a car-body, and a truck-frame, the car being pivoted to the truck over an axle thereof, of coacting car rub-plates and truck-bearings spring-supported over an axle, and a coacting truck-bearing and car rub-plate having an aligned and reverse-incline contact-surface, the truck-bearing being spring-supported on the truck ad-

jacent the axle and in line with the longitudinal center of the truck, substantially as described.

9. The combination with the car-body and the truck pivoted thereto, a center bearing, the car and truck having reverse-incline rub-plates, a pivot pin or bolt, a spring on the bolt, a seat for the spring secured fast to the bolt, and a seat on the spring to receive the weight of the car, substantially as described.

10. A car-body and a pivoted truck-frame, wheels for the frame, and the interposed coacting rub-plate C⁸ and bearings C⁷ each having compound reverse-incline contact-surfaces comprising the mediate horizontal portions C¹⁰ and upwardly-inclined portions C⁹ converging from the said mediate portions, substantially as described.

11. The combination with a truck having end cross-bars c², the brackets h³ extending inwardly from the cross-bars and secured thereto, links h² pendent from the brackets, shoes on the links, beams connecting the shoes, and an upright lever h⁴ pivoted to one beam between the former's ends, and a link h⁵ engaging the lower end of the lever h⁴ and the opposing brake-beam, substantially as described.

Signed at Boston, in the county of Suffolk and State of Massachusetts, this 2d day of July, 1894.

JOHN A. BRILL.
